(57) **CLAIM**

The ornamental design for a package having surface ornamentation and window, as shown and described.

DESCRIPTION

The present application file contains at least one drawing executed in color. Copies of this patent or patent application publication with color drawing(s) will be provided by the Office upon request and payment of the necessary fee.

FIG. 1 is a perspective view of the first embodiment of a package having surface ornamentation and window;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof;

FIG. 7 is a bottom plan view thereof;

FIG. 8 is a perspective view of a second embodiment of a package having surface ornamentation and window;

FIG. 9 is a front elevation view thereof;

FIG. 10 is a left side elevation view thereof;

FIG. 11 is a rear elevation view thereof;

FIG. 12 is a right side elevation view thereof;

FIG. 13 is a top plan view thereof; and,

FIG. 14 is a bottom plan view thereof.

The broken lines and the areas within the broken lines on the rear, sides and bottom depict portions of the package having surface ornamentation and window that form no part of the claimed design. On the front of the article shown in FIGS. 1, 2, 8 and 9, all of the inner broken line features and areas within them depict portions of the package having surface ornamentation and window that form no part of the claimed design.
